PORTABLE BEVERAGE DISPENSER

Earl F. Rutan, Pound Ridge, N. Y., assignor to The Coca-Cola Company, New York, N. Y., a corporation of Delaware

Application June 21, 1955, Serial No. 36,620

Term of patent 14 years

(Cl. D2—3)

FIG. 1.

FIG. 2.

FIG. 3.

FIG. 4.

Fig. 1 is a view in front perspective of a portable beverage dispenser embodying my new design;

Fig. 2 is a top plan view on a slightly enlarged scale thereof with the handle in lowered position;

Fig. 3 is an enlarged side view of said dispenser; and
Fig. 4 is a front view thereof.

I claim:

The ornamental design for a portable beverage dispenser, as shown.
